VENTILATING SPRING CUSHION

Samuel P. Crane, Great Neck, N. Y., assignor to R. O. Kent Co., New York, N. Y., a copartnership consisting of said Crane and Stephen D. Kent

Application June 10, 1954, Serial No. 435,660

6 Claims. (Cl. 155—182)

This invention relates to spring seat cushions of the type permitting circulation of air therethrough for ventilating purposes.

The invention contemplates the provision of an inexpensive ventilating spring cushion adapted to be assembled with a minimum of labor, all of the main spring turns inside of the border frame being designed to be stitched, knitted or locked together against separation after being arranged in position, in which position a locking spring is pushed laterally into said turns of a main spring, the locking being accomplished merely by a straight substantially undistorted knitting wire passing through the interior of the locking spring and engaging and crossing a coil of each turn of the main spring.

The invention further contemplates the provision of simple and effective stitching means for the various spiral turns of the main coil spring, said means employing a straight locking coil spring crossing and pushed into all of said turns at the crossing points to interlace with the main spring at approximately right angles and a substantially straight knitting wire arranged longitudinally inside of the locking spring and thereby knitting and locking the spiral turns of the main spring to the locking spring at the desired intervals.

The invention further contemplates the provision of simple means for preventing dislocation of the locking spring, said means including indents at the corners of the border wire frame in which the knitting wire is secured.

The various objects of the invention will be clear from the description which follows and from the drawings, in which,

Fig. 1 is a plan view of the assembled spring portion of the cushion as it appears preparatory to the insertion thereof within a suitable ventilating cover.

Fig. 2 is a fragmentary perspective view of portions of a pair of adjacent spiral turns of the main coil spring, the locking spring and the knitting wire, showing how said wire stitches aligned coils of the turns to the locking spring.

Fig. 3 is a fragmentary top plan view of one form of the means for holding the end of the locking spring to the border frame.

Fig. 4 is a fragmentary combined vertical sectional view and elevational view of the springs and the stitching wire viewed substantially in the direction of the axis of the locking spring.

Fig. 5 is a fragmentary top plan view of a typical locking structure for a main spring coil.

In that form of the invention shown herein, the main spring 10 is arranged with one end 11 thereof near the center of the cushion and the other end 12 near the wire border frame 13, each of said ends being preferably bent to engage a coil and thereby to hold the spring ends in place. Said main spring is sufficiently flexible to enable it to be bent into spiral form and to provide a number of turns or convolutions 10a, 10b, 10c, 10d and the like as best seen in Fig. 1. The turns may be closely adjacent each other, or slightly spaced apart or even overlapping

if desired, depending on the density of the spring structure required. Similarly, the pitch of the coils may vary considerably. The main spring 10 is merely set within the generally rectangular frame 13, a border spring as 14 being mounted on and surrounding the frame. For economy of construction, there need be no direct connection between the main spring and the frame or border spring, but the turns of the main spring are substantially parallel to or concentric with the frame.

Simple and inexpensive means are provided to secure the various turns of the main spring against dislocation from the proper positions thereof relatively to each other and to the frame 13. Said means comprises the transversely arranged preferably straight coil springs 15, 16 which cross and are interlaced with the turns 10a, 10b, 10c and the like throughout the length and width of the cushion, approximately at right angles at the crossing points, and the straight knitting wires 17, 18. The wire 17 passes completely through the entire length of the locking spring 15 and the wire 18 similarly passes through the locking spring 16. The diameter and pitch of the locking spring may vary considerably. As shown, said springs are smaller in diameter than the main spring and are of relatively small pitch, though it will be understood that the diameter of the locking springs may well be increased at least up to that of the main spring, if desired, without adversely affecting the locking action.

To insure the proper locking effect, those corresponding coils as 20a, 20b, 20c and the like of the various turns 10a, 10b, 10c and the like, which are arranged at or which cross a locking spring are moved into aligned relation to each other in the direction of the axis of the locking spring, as best seen in Fig. 2, before the stitching operation by means of the knitting wire, is performed. The coils being flexible, they may easily be manually shifted or compressed slightly if necessary to effect such alignment, and hence the coils assume the same relative positions with respect to a selected number of the coils of the locking spring.

As shown in Fig. 5, that locking coil of the locking spring which extends between the points 34, 24 and 35 is open at the left and permits the entry thereto of one end part 36 of the lockable coil 20c of a turn 10c of the main spring 10 when the springs are pushed together. Similarly, the locking coil extending between the points 34a, 24a and 35a is open at the left and permits the other end part 37 of the lockable coil 20c to enter therewithin. All of the lockable coils such as 20a, 20b, 20c and the like, are simultaneously locked or knitted to the locking spring by passing the knitting wire 17 or 18 through the entire length of and inside of the locking spring, and preferably on the same side of, and in the same relation to, the corresponding coils 20a, 20b, 20c etc., of the various turns. Such locking is readily accomplished by means of a suitable needle-like member carrying the knitting wire, the member being thrust rapidly and effectively through the locking spring to arrange the wire between the coils of the locking spring and the lockable coils of the main spring as the wire advances through the locking spring.

The lockable coils are preferably aligned, or in other words, they are arranged in the same relative positions with respect to each other and with respect to the respective locking coils of the locking spring within which they are confined, as shown in Fig. 2.

If desired, a single length of annealed wire may be employed for both knitting wires 17 and 18. As shown, after the wire 17 is passed through the spring 15 from the lower right hand end, as shown in Fig. 1, to the upper left hand end, the wire is passed to the outside of and around the frame 13. The wire is then carried across the cushion to the upper right hand end of the spring 16 and passed through said spring to the lower left hand end thereof, then carried around the frame and across the

cushion to the point of beginning and there joined to the other end of the wire length by twisting or the like as at 23 (Fig. 1). Obviously, two separate lengths of wire may be used, each end of each wire being secured to the frame or to the end portion of the adjacent locking spring.

Preferably though not necessarily, the springs 15, 16 and the interior wires 17, 18 therein, are arranged diagonally or diametrically of the cushion and of the frame. To prevent shifting of the ends of said springs along the frame, a suitable indent as 21 is made at each corner of the frame. The end of the locking spring is secured to the indent at the bend 22 thereof in any suitable manner as by means of the end loop on the locking spring as best seen in Fig. 3. As many locking springs as is deemed necessary are used, but I have found that two such diagonally arranged intersecting springs are sufficient for normal purposes. If desired, the indents at the corners may be omitted, and if the frame is rectangular in outline the springs may be arranged to extend from about the middle of one side or end edge to the middle of the opposite side or end edge. Whatever the shape of the frame, two crossing locking springs hold each of the various turns of the main spring at four points at least, that is, at two points of each turn on opposite sides respectively of the cushion for each locking spring, thereby adequately preventing undue displacement of the turns. It will be understood that to interlace the locking spring with the turns of the main spring, the straight locking spring is arranged to cross the turns, as for example, by resting on top of the main spring turns, the locking spring being then pushed downwardly or downwardly and transversely into the main spring turns until the axis of the locking spring is substantially coplanar with the axis of the turns as best seen in Fig. 4.

The coils 20a, 20b and the like of the main spring turns may possibly assume various positions with respect to the knitting wire, depending on the positions in which said coils are aligned prior to the stitching thereof by said wire. As shown in Fig. 5, the diametrically opposed parts 36 and 37 of the lockable coils 20c are on the same side, namely, the right hand side of the knitting wire so that neither of said parts 36 or 37 can leave the locking coil within which it is confined. That is, neither part can move more than the inner diameter of the locking coil because the wire limits such movement toward the left and bridges the gap or space between end points as 34 and 35 of the locking coil of the locking spring at the space where the coil 20c might leave the locking coil, which is the same space through which the coil entered the locking coil. Movement of the coil 20c toward the right is prevented by the intermediate parts 24, 24a of the respective locking coils. Should one part as 36 of the lockable coil 20c become arranged on the left hand side of the knitting wire during the stitching operation at the space between the ends 34 and 35 of the locking coil, the other end of said lockable coil 20c is nevertheless adequately locked in place between the wire and the part 24a of the locking coil. Should it be noted during the stitching operation that the part as 36 of the lockable coil is not in the proper position, it may readily be pushed manually into position for locking. That is, the part 36 may be in the wrong place in the isosceles triangle which constitutes the horizontal projection of the locking coil and the bridging part of the wire 18, the wire being the base of the triangle and the coil parts 34, 24 and 24, 35 being the equal sides of the triangle. In that case, said part 36 is merely moved, as it easily can be, to the proper position within the triangle mentioned to permit the wire 18 to pass to the left of said part 36 as viewed in Fig. 5.

Normally, at least some one point of a coil of the main spring will fall or be caused to fall within the locking spring to be confined between the knitting wire and a locking coil of the locking spring, so that the maximum possible movement of the lockable or locked coil of the main spring is limited to less than the inner diameter of

the locking spring. Ordinarily and preferably, two opposed parts 36 and 37 of the lockable coil of the main spring are confined as described inside of the locking coil, though in some cases only one of said parts of a particular coil may be caught and locked and the other missed, or only one point of each lockable coil may be deliberately caught and locked if desired.

Optionally, an additional auxiliary spring as 25, (Fig. 1) may be attached to or be passed around selected sides of the frame as at 26, 27 and 28 and cross a number of the turns of the main spring, thereby to increase the density of the coils in the cushion. The ends of the spring are secured to the main spring by bending said ends as at 29, 30. Said auxiliary spring may be woven over and under the respective alternate turns of the main spring to form a better lock, if desired.

It will now be seen that I have provided a simple, economical but efficient ventilating cushion quickly and easily assembled and well designed to carry out the objects of the invention. While certain specific forms of the invention have herein been shown and described, various obvious changes may be made therein without departing from the spirit of the invention defined by the appended claims.

I claim:

- 25 1. In a ventilating spring cushion having a plurality of rows of spring coils, means for securing said rows against displacement comprising a locking coil spring having a substantially straight axis and interlaced with and crossing successive rows, and a substantially straight knitting wire confined loosely within the interior of the locking spring in substantially parallel relation to the axis of the spring, said wire passing through and confining a spring coil of each row within the interior of the locking spring at a point where the locking spring crosses the row.
- 30 2. The spring cushion of claim 1, the knitting wire being adapted to be inserted into its operative position within the locking spring by a single straight line movement, the locking spring crossing the rows at approximately right angles and being adapted to be confined within the rows at the crossing points by a pushing movement.
- 35 3. In a ventilating spring cushion, a main coil spring having a plurality of turns arranged in a spiral, and a pair of helically coiled locking springs arranged diametrically of the cushion and crossing each other and also crossing and interlaced with the turns of the main spring, part of a lockable coil of the main spring being arranged within the interior of a locking coil of the locking spring at each crossing point of the locking springs and the turns, the locking spring being adapted for assembly with the main spring by pushing the springs laterally together until the axes thereof are coplanar.
- 40 4. The spring cushion of claim 3, and a straight knitting wire arranged longitudinally within the interior of the locking spring and bridging the locking coil in a position beyond said part of the lockable coil and thereby confining the lockable coil within and against movement out of the inside of the locking coil, the horizontal projection of the locking coil and the bridging portion of the straight wire being substantially an isosceles triangle, of which said bridging portion is the base and the locking coil the two equal sides, said part of the lockable coil being permanently confined within the triangle by the bridging portion of the straight wire.
- 45 5. In a ventilating cushion having a main spring provided with a plurality of substantially concentric turns, the improvement comprising a locking spring having helical coils of uniform diameter substantially perpendicularly crossing and interlaced successively with the respective
- 50 60 65 consecutive turns of the main spring, said springs being adapted to be interlaced by pushing the springs together, one part of a lockable coil of each of the successive turns of the main spring being arranged within the interior of a locking coil of the locking spring, the other opposite part of the lockable coil being arranged within the interior
- 70 75

of a different locking coil of the locking spring, and a straight wire loose within the interior of the locking spring and extending past both said parts of the lockable coil in position to confine said parts within the respective locking coils, said wire being insertable and confined within the aforesaid coils of said springs by a single straight line movement.

6. In a ventilating spring cushion, a plurality of rows of spring coils, the axes of the respective rows being coplanar, and means for securing said rows at respective corresponding aligned points thereof in the coplanar relation thereof and against substantial transverse and longitudinal displacement at said points comprising a locking coil spring crossing said rows at said points, the axis of the locking spring being substantially straight and coplanar with the axes of the rows, corresponding parts of the respective rows being aligned, each of said parts embracing a number of coils of the locking spring and entering into the interior space in one of said coils of the locking spring adjacent one of the aligned crossing points, and a knitting wire arranged within the interior of the locking spring and bridging the spaces between the respective points where each coil of the locking spring

begins and where the coil ends, said respective points of beginning and ending being aligned, said wire being straight and passing substantially perpendicularly through said rows consecutively at said aforementioned crossing points, the horizontal projection of the coil of the locking spring and of the bridging portion of the wire at each of said crossing points being a triangle of which the bridging portion constitutes the base and the coil of the locking spring constitutes the other two sides, said corresponding parts of the respective rows being confined within the triangle by the bridging portion of the wire.
